UNITED STATES PATENT OFFICE.

ALEXANDER MALM, OF NEW YORK, N. Y., ASSIGNOR TO THEODORE W. SHERIDAN, OF BROOKLYN, NEW YORK, AND CHARLES B. SHERIDAN, OF ORANGE, NEW JERSEY.

PAPER-CUTTING MACHINE.

SPECIFICATION forming part of Letters Patent No. 443,398, dated December 23, 1890.

Application filed August 28, 1890. Serial No. 363,287. (No model.)

To all whom it may concern:

Be it known that I, ALEXANDER MALM, a citizen of the United States, residing at New York, in the county and State of New York, have invented new and useful Improvements 5 in Paper-Cutting Machines, of which the following is a specification.

This invention relates to improvements in paper-cutters; and the invention consists in 10 the details of construction set forth in the following specification and claims and illustrated in the accompanying drawings, in which—

Figure 1 is a face elevation of a paper-cutter containing the invention. Fig. 2 is a plan view of Fig. 1. Fig. 3 is a section along xx , Fig. 1. Fig. 4 is a section along yy , Fig. 2. Fig. 5 is a section along zz , Fig. 3. Fig. 6 is a section along vv , Fig. 1.

In the drawings, the letter A indicates a 20 support or frame, having a table B for the paper C, as also a clamping-bar D and cutter or blade E to clamp and cut the paper.

F is the cutter-head.

The construction and operation of these 25 parts are well known and need no detailed description.

The driving-shaft G has the usual fast and loose pulleys H H and a fly-wheel I. Said shaft G gives motion to the driving-gear composed 30 of the two pinion parts or wheels K L. The actuating-gear M moves the cutter E to its work, and the returning-gear N returns the cutter to the starting-point. The gear M is engaged by the pinion K and the gear N by 35 the pinion L. The gears M N are each shown in the form of mutilated or segmental gears mounted on the shaft O, and they have crank-pins P, connected by links Q to the cutter. The pinion parts K L are of different sizes, as 40 are also the gears M N, so that the cutter is moved to the work slowly and with considerable force, and when the work is finished the cutter is returned rapidly to its starting-point. The pinion L has twice the number of teeth 45

of the pinion K. The teeth of the pinions K L are so situated (see Fig. 6) that the radii or radial planes drawn from the center of the pinion K through two adjacent teeth in said pinion will pass through two teeth of pinion

L, leaving an intermediate tooth located between said two teeth of pinion L.

In Fig. 3 the parts are indicated in the position occupied when the knife is about to move toward the work. The actuating-gear M, moving in the indicated direction, is engaged by the pinion part K, and as the diameter of gear M is large and that of pinion part K small the shaft G has considerable leverage, so that it can move the knife to the work with considerable force. When the gear M has 60 passed the pinion part K, the returning-gear N is engaged by the pinion part L, and by reason of the reduced diameter of gear N and of the increased diameter of pinion part L the knife is returned rapidly to its starting-point without the shaft G having to alter its speed. The gears M N carry a stud or inclined projection R, which, when the cutter has returned to the starting-point, strikes the finger S, Fig. 1, connected to the lever T U fulcrumed 70 at V. Said lever actuates the clutch W, which connects the shaft G and driving-pinion K L. When the stud R strikes the finger S, the clutch-actuating lever is moved, so as to throw the clutch out of action and stop the machine 75 when the cutter has reached the starting-point. The lever T U carries a set-screw X, which can be so adjusted that when the lever T U is moved to release the clutch the screw X presses upon a brake or strap Y, so as to 80 tighten said brake about the driving-pinion K L and promptly stop the machine. Fig. 4 shows the pinion K L provided with a suitable drum engaged by the brake-band Y. A hand-lever a Z, fulcrumed at b, is connected to the 85 clutch-lever T U, and said hand-lever can be used to move the clutch-actuating lever, so as to bring the clutch into its engaging position when the machine is to be started. When the clutch is in its released position, the arm a of 90 lever a Z is engaged by spring c, so that the clutch is locked against accidental engagement.

What I claim as new, and desire to secure by Letters Patent, is—

1. In a paper-cutting machine, the combination, with the cutter or blade, of a driving-shaft, an actuating-gear, and a returning-gear

connected with the cutter or blade, a pair of pinions arranged on the driving-shaft and connected to rotate in unison, and a clutch serving to connect both pinions with the shaft for 5 simultaneously rotating such pinions, substantially as described.

2. In a paper-cutting machine, the combination, with the cutter or blade, of a segmental or mutilated actuating-gear and a segmental 10 or mutilated returning-gear, and driving-pinions K L, made to engage the actuating and returning gears, substantially as described.

3. In a paper-cutting machine, the combination, with the cutter or blade, of an actuating 15 and a returning gear for said blade, driving-pinions for the actuating and returning gears, a driving-shaft, a clutch made to connect the driving-shaft and driving-pinions, an actuating-lever for the clutch, and a stud or 20 projection carried by the actuating and returning gears for moving the lever and clutch 25

to the releasing position, substantially as described.

4. In a paper-cutting machine, the combination, with the cutter or blade, of an actuating 25 and a returning gear for said blade, driving-pinions for the actuating and returning gears, a driving-shaft, a clutch made to connect the driving-shaft and driving-pinions, an actuating-lever for the clutch, a brake 30 connected to the actuating-lever, and a stud or projection carried by the actuating and returning gears for moving the lever and clutch to the releasing position and for tightening the brake, substantially as described. 35

In testimony whereof I have hereunto set my hand in the presence of two subscribing witnesses.

ALEXANDER MALM.
